Primary Examiner—Catherine Tuttle*Attorney, Agent, or Firm*—H. Jay Spiegel**[57] CLAIM**

The ornamental design for a support device for elongate members, as shown and described.

DESCRIPTION

FIG. 1 shows a top view of my claimed design;
FIG. 2 shows a right side view of my claimed design;
FIG. 3 shows a left side view of my claimed design;
FIG. 4 shows a bottom view of my claimed design;
FIG. 5 shows a front view of my claimed design;
FIG. 6 shows a rear view of my claimed design; and,
FIG. 7 shows a perspective view of my claimed design.
